UNITED STATES PATENT OFFICE.

NORMAN SCOTT-RUSSELL, OF LONDON, ENGLAND.

COMBINED DOOR CHECK AND SPRING.

SPECIFICATION forming part of Letters Patent No. 446,561, dated February 17, 1891.

Application filed April 21, 1890. Serial No. 343,805. (No model.)

To all whom it may concern:

Be it known that I, NORMAN SCOTT-RUSSELL, a subject of the Queen of Great Britain, residing at 41 Coleman Street, E. C., in the city of London, in the county of Middlesex, England, have invented a new and useful Improvement in a Combined Door Check and Spring, of which the following is a specification.

10 My invention relates to improvements in means for making doors self-closing, and at the same time to make the closing noiseless. I attain these objects by the mechanism illustrated in the accompanying drawings, in 15 which—

Figure 1 is an elevation, and Fig. 2 a plan, of the apparatus; and Fig. 6 shows it in two positions, with the door closed and with it fully open, the remaining figures relating to 20 details and to an alternative arrangement.

Similar letters refer to similar parts throughout the several views.

Referring to Figs. 1 and 2, the apparatus consists of the bracket *a*, attached to the top 25 member of the fixed door-frame by screws, and carrying at its end the screw *b*, which thus forms a fixed fulcrum. The bracket *c* is fixed to the door itself, near the top, and has two lugs *d*, through which the pin *e'* passes 30 and forms a moving fulcrum. The bell-crank lever *e* is made stirrup-shaped, so as to come outside the lugs *d* of the bracket, and is fixed by screws onto the plate *f*. It is provided with a hole *g*, into which a pin goes and carries the 35 rod *h*, and also with a hole *i*, through which one end of a spiral spring *m* passes, the other end being attached to the projection *j*, which forms part of the bracket *c*. The piece *k* is formed with two parallel arms, through which 40 the pin *e'* passes, and is fixed to the plate *f'*. The other end of each arm *k* is provided with a spring *l*, which tends to keep it against the door when the door is closed.

Fig. 3 is a side view of the rod *h*, and Fig. 45 4 a side view of bracket *a*.

Fig. 5 is a view of the top plate *f* of the bellows, provided with a screw *n*, by which the escape of air from the bellows may be regulated, as it is cut away at one side. *p* is the 50 inlet-valve, with a spring attached, arranged in a hollow seating *q*. The bellows *o*, which is

made of india-rubber or other suitable material, is fixed at the ends to the plates *f* and *f'*.

Figs. 7 and 8 show two methods of attaching it. In Fig. 7 a wire *r* is passed outside the india-rubber and is tightened, so as to hold the india-rubber in the groove. In Fig. 8 the india-rubber itself is made with a solid ring at the end, which holds the bellows firmly onto the plate *f*, being stretched at first so as to 60 pass over the point *s*.

In Fig. 6 the dotted lines show the apparatus when the door *t* is closed. The full lines show it when the door is fully open. As the door opens, the spring *m* is stretched, the rod *h* 65 describes an arc on *b* as a center, and the springs *l* prevent the part *k* from rising until the bellows *o* is completely expanded by the combined movements of the rod *h* and the pivot *d* and lever *e*. It has thus become filled 70 with air through the valve *p*. If now the door *t* be let go, the spring *m* will cause it to close, and when the part *k* strikes the door the bellows will be compressed by the movement of *e*, and as the air can only escape slowly through 75 the regulating-screw *n* the door will close silently.

Fig. 9 represents an alternative arrangement of Fig. 6, in which the bottom plate *f'* of the bellows *o* is fixed to the door *t*. The top 80 plate *f* has a radius-bar *u* attached to it, so that it describes an arc with the point *e'* as a center. Upon *f* is placed a cone-shaped box *v*, in which a spiral spring *w* is fixed and keeps the bellows normally distended, the conical 85 box being required merely to allow more length of spring to be used. The end *x* of the lever *e* is not fixed to the plate *f*, as in the other views, but is formed as a foot, which the bellows strikes as the door closes. In the reverse action of opening the door the bellows 90 expands and is followed by the foot *x* to a certain distance, after which the bellows leaves the foot and the two parts occupy the positions shown in Fig. 9. The action depends 95 upon the same principle as set forth in the previous figures.

I am aware that prior to my invention combined door checks and springs have been made in which the spring has caused the door 100 to close, while the check has depended upon the compression of air in a chamber from

which it could gradually escape. I therefore do not claim such a combination, broadly; but

What I do claim, and desire to secure by Letters Patent, is—

- 5 1. The combination of the two brackets *a* and *c*, one fixed on the door and one on the door-framing, with the rod *h*, lever *e*, spiral spring *m*, bellows *o*, lever *k*, and springs *l*, for the purpose of closing a door silently, all substantially as set forth.
- 10 2. The combination, with the bell-crank lever *e*, provided with a forked end pivotally attached to the door and a projecting plate at its middle part for bearing against the bellows, of the rod *h*, pivotally connecting the
- 15

free end of the said lever with the door-frame, the spring *m*, secured at one end to the free end of the said lever and at the other end to the door between the forked portion of the said lever, and the flexible bellows adapted to be compressed by the said projecting plate before the closing of the door is completely effected, substantially as set forth. 20

In testimony whereof I hereby affix my signature in presence of two witnesses.

NORMAN SCOTT-RUSSELL.
